[57] **CLAIM**

The ornamental design for a detachable arm rest for motor vehicles, as shown and described.

DESCRIPTION

FIG. 1 is a top, front perspective view of a detachable arm rest for motor vehicles according to my design;

FIG. 2 is a side elevational view thereof, the opposite side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of a detachable arm rest for motor vehicles showing a second embodiment of my new design; and,

FIG. 8 is a side elevational view of FIG. 7, the opposite side being a mirror image that side shown in FIG. 7.
